[57] CLAIM

The ornamental design for a styling head, as shown and described.

DESCRIPTION

FIG. 1 is a top, left side, front perspective view of a styling head showing my new design attached to the barrel of a hair dryer;

FIG. 2 is a left side elevational view thereof, the right side being a mirror image of the left side shown;

FIG. 3 is a bottom view thereof; and,

FIG. 4 is a front view thereof.

The broken line showing of the hair dryer barrel is for illustrative purposes only and forms no part of the claimed design.
